UNITED STATES PATENT OFFICE.

NATHAN A. BRUSH, OF JOLIET, ILLINOIS, ASSIGNOR TO THE GREIF BROS. COOPERAGE CO., OF CLEVELAND, OHIO, A CORPORATION OF DELAWARE.

HEAD FOR BARRELS.

Application filed March 18, 1926. Serial No. 95,533.

My invention relates to barrel heads and more particularly to stamped steel heads, it being the purpose of the present invention to provide these steel heads in place of the usual wooden heads now in use.

A further object of the invention is to provide a means for securing these heads to the barrels in a manner more simple and much stronger than the means employed at the present time.

Another object of the invention is to provide a head capable of being used indefinitely and so constructed that the cost of manufacture, in connection with its life, is greatly reduced as compared with the heads as now used.

With the objects above indicated and other objects hereinafter explained, in view, my invention consists in the construction and combination of elements hereinafter described and claimed.

Referring to the drawings, Fig. 1 is an elevation view of a barrel, partly in section, and embodying my invention.

Fig. 2 is a top plan view of the head showing the means for securing the head to the barrel and a means for reinforcing the head.

Fig. 3 is a segmentary sectional view showing the head secured in the barrel with the base portion of the head extending toward the inside of the barrel.

Fig. 4 is the same except that the base portion of the head is reversed, or extends outwardly.

In the drawings 1 indicates a barrel of the usual construction; 2 and 3 the wires for reinforcing the barrel and holding the slats in their proper position, 4 the hoop at the top of the barrel and 5 the hoop at the bottom, the hoops being secured in place by tacks or nails 4^a driven into the barrel 1. All of this is the usual construction and forms no special part of the invention.

At the top of the barrel 1 and upon the inside there is usually provided, and should be in the present case, a circumferential groove 6 having a cross section forming a V. The groove 6 has a lower side 7 and an upper side 8 and the opening of the groove 6 extends inwardly.

At the bottom of the barrel 1 the same condition exists. There is a circumferential groove 9 formed near the bottom of the barrel 1 and on the inside thereof. This groove 9 is V-shaped in cross section and has an

upper side 10 and a lower side 11 and likewise has the opening extending inwardly.

It is customary to provide a wooden head for the barrel 1. This wooden head is constructed of several sections of wood and having formed at its outer edge a beveled portion which is adapted to engage the V-shaped groove 6 or 9 within the barrel 1. In using the wooden head it has been found to be very objectionable in that any heavy load which falls upon the head usually smashes it and exposes the contents or spills it. Likewise very often the barrel is accidentally dropped or pushed from off a platform to the ground and as a result the contents within the barrel, nails, for instance, forces out the head or breaks it so that again the contents is spilled.

To avoid the possibility above set forth, I provide a head 12 formed from a sheet of steel or other suitable metal and having a diameter substantially equal to the inside diameter of the barrel. The head 12 comprises a flat base portion 13 provided at its outer edge with an annular flange 14. The annular flange is V-shaped and is so arranged that the opening of the flange extends inwardly, said flange being formed with a leg 15 integral with the flat portion 13 and a leg 16 integral with the leg 15. The V-shaped flange is formed to fit within the groove 6 or 9 formed at the top and bottom of the barrel 1 and on the inside thereof.

To provide a means for securing the head within the barrel 1 and consequently within the grooves 6 and 9 each leg of the annular flange 14 is provided with burrs, or other means, which extend outwardly with respect to the flange and are adapted to engage and be embedded in the wood of the barrel 1 within the grooves 6 and 9. The burrs 17, shown here as triangularly shaped portions, are provided on the leg 16 and similar burrs 18 are provided on the leg 15 of the annular flange 14. These burrs are spaced as desired but it has been found best to stagger or alternate the burrs in the adjacent legs. That is, the burrs 17 are positioned upon the leg 16 and the burrs 18 are positioned upon the leg 15 so that each burr 18 is in the center of the space between the burrs 17 and the leg 16.

These burrs 17 and 18 are further arranged so that they extend substantially at right angles to the angle of the legs 15 and 16 of the annular flange 14. This permits

the burrs to take a firm hold in the grooves 6 and 9 of the barrel 1.

When it is desired to attach the head 12 to the barrel 1 the head is forced down into the groove 6 so that the legs 15 and 16 of the annular flange 14 engage the sides 7 and 8 of the groove 6. The burrs 17 and 18 carried by the annular flange 14 are forced into the wood around the groove 6 and 19 secure a firm footing. The hoop 4 is then placed upon the outside of the barrel at the top and forced downwardly until the head 12 is firmly within the groove 6 and the burrs embedded in the wood of the 15 groove. The hoop 4 is then held in place by means of tacks or nails 4^a and the head is prevented from becoming disengaged.

The same procedure takes place in securing the head 12 to the bottom of the barrel 20 within the groove 9.

It has been found desirable in many instances, in the filling of the barrel or keg to have some extra space for packing at the top or bottom of the barrel. With the use of the 25 wooden head this additional space could not be obtained. However, it is my purpose to so construct my head 12 that one or two inches additional space within the barrel may be provided for.

30 Referring particularly to Figs. 3 and 4 of the drawings I have shown a segmentary detail of the arrangement of the head. In Fig. 3 it will be noted the usual barrel 1 and the usual groove 6 formed at the top and 35 within the barrel. The head 12 with its V-shaped annular flange 14 and its flat bottom portion 13 is shown engaging the groove 6 and so disposed therein that the flat bottom portion 13 extends interiorly of the barrel 1. 40 The same condition exists with respect to the head fitted within the groove 9 at the bottom of the barrel.

Now if, as has been heretofore stated, it 45 is desired to have several inches additional space, for packing for instance against breakage, etc., it is only necessary to reverse the head 12 at the top and bottom of the barrel 1. That is, reverse the head 12 so that the flat bottom portion 13 extends outwardly with respect to the interior of the barrel and the distance gained is the distance from the flat bottom portion 13 to the 50 top of the annular flange 14.

55 There is a possibility that if the barrel should fall from any height the flat bottom portion 13 of the head 12 might be inclined to twist. To eliminate this possibility and to insure the substantial formation of this head 12, a reinforcing rib 19 in the shape of a V or any other appropriate shape is 60 pressed into the flat bottom portion 13. This has been found to be a very efficient means of reinforcement.

In further explanation of the burrs 17

and 18 and the reason for the specific arrangement herein described, if the position of the burrs 17 and 18 is carefully noted it will be seen that they extend substantially at right angles to the legs 15 and 16 and consequently to the sides 10 and 11 of the groove 6. This permits the burrs to secure a good footing in the wood surrounding the groove 6. Now, if the barrel or keg 1 should accidentally fall and strike on its end, the bottom end, for instance, the contents within the barrel will be thrust against the head 12 and consequently, instead of breaking the head as would be the case with the use of the wooden head, causes the burrs 17 on the leg 16 to be forced further into the wood surrounding the groove 6 and thereby secure a more firm hold. The result is the same if the barrel falls upon the opposite end. It is likewise the same if the barrel falls when the head 12 is in the reversed position except that the burrs 18 on the leg 15 are the ones to be forced into the wood of the flange 6.

70 The particular construction set forth is for the purpose of explanation and embodies the preferred construction of my head but many other forms may be resorted to without deviating from the spirit of the invention as read with the appended claims.

75 Having thus described my invention, I claim:

1. In combination with barrels and the like, a head comprising a sheet of metal provided with a substantially V shaped flange formed at its outer edge and adapted 100 to engage a croze provided in the barrel, depending burrs in the lower portion of the flange and inclined burrs in the upper portion of the flange, arranged alternately with respect to both portions of the flange, said 105 burrs adapted to engage the croze in said barrel.

2. A head for barrels and the like comprising a sheet of metal having a circumferential flange, said flange being formed of two legs angularly disposed with respect to each other and to the sheet of metal and adapted to fit within the croze of a barrel, and burrs formed on each leg, respectively, and adapted to engage the barrel in opposite 110 directions.

3. A head for barrels and the like comprising a sheet of metal having a substantially V-shaped inwardly facing circumferential flange adapted to fit within the croze 120 of a barrel, said substantially V-shaped flange being provided with burrs formed on the leg thereof and projecting in opposite directions from each other so as to engage the barrel in opposite directions.

125 In testimony whereof, I hereunto affix my signature.

NATHAN A. BRUSH.
